UNITED STATES PATENT OFFICE.

LEO PLATT, OF NEW YORK, N. Y.

DESIGN FOR RIBBON.

Application filed March 16, 1922. Serial No. 1,205. Term of patent 7 years.

To all whom it may concern:

Be it known that I, LEO PLATT, a citizen of the United States, residing at 210 Cathedral Parkway, New York, New York, have invented a new, original, and ornamental Design for Ribbon, of which the following is a specification, reference being had to the accompanying drawing, forming part thereof, wherein—

Figure 1 is a face view of a ribbon, embodying the new design, Fig. 2 is a section on the line 2—2 of Fig. 1 and Figure 3 is an enlarged detail fragmentary view showing more clearly the open work longitudinal

section and the contrasting surfaces of the different sections.

The ribbon which is woven complete by the loom consists of sections having smooth satin like surfaces alternately arranged with a hemstitched section, and an upstanding grosgrain section, one of the side margins of the ribbon having a picot edge. The sections are of any appropriate contrasting colors.

I claim:

The ornamental design for ribbon as shown and described.

LEO PLATT.
